3 Claims. (Cl. 102—92.5)

The present invention relates generally to protective devices for aerial vehicles; more particularly it relates to improved displaceable seals for use with pressure probes or radomes of guided missiles.

This application is a division of U.S. patent application Serial No. 792,936, filed February 12, 1959, now Patent No. 2,987,999, issued June 13, 1961, by the present applicants.

Guided missiles require information regarding static pressures and/or ram pressures in order to maneuver properly. Such missiles ordinarily employ pressure probes and/or radomes having ports connected with appropriate equipment for measuring such static or ram pressures. It is important that these ports be kept free of foreign bodies if the measuring equipment is to function properly. That is, during the handling of guided missiles prior to launching thereof they may be subjected to a variety of environmental conditions which would be deleterious to the proper functioning of pressure measuring equipment. Such conditions would include ocean waves, high winds, ice, shock, and vibration. Moreover, since the launching of a guided missile is a complicated operation under optimum conditions, it is desirable that seals be provided that will remain in place during handling and launching operations but which will be removed automatically and positively after the missile has been launched.

The invention seeks, as object, to provide a displaceable seal which may be used for closing the port or ports of a missile nose probe until after missile launching.

A further object of the invention is to provide a displaceable seal which employs a low melting point alloy for securing said seal in position on a missile nose or nose probe, which alloy may only be melted by the coincident occurrence of a high velocity air flow and the resultant high stagnation temperature which occurs only during missile flight.

Still another object of the invention resides in the provision of a displaceable seal which will be characterized by its extreme simplicity and ease of application.

Other objects and many of the attendant advantages of this invention will be readily appreciated as the same becomes better understood by reference to the following detailed description when considered in connection with the accompanying drawings, wherein:

FIG. 1 is a side elevation, partly in section, showing an embodiment of the invention, the positions of the sections of the seal being shown in broken lines as they would appear immediately prior to separation from a missile nose probe;

FIG. 2 is a front elevation of the embodiment shown in FIG. 1; and

FIG. 3 is a front elevation showing a modified slot arrangement for use with the embodiment of FIGS. 1 and 2.

Referring now to the embodiment of the invention shown in FIGS. 1, 2 and 3, the numeral 21 indicates a pressure probe which is mounted on the nose of a missile, a portion of which nose is shown at 22. The probe 21 is formed in its side wall with an inlet port 23. The protective device constituting the embodiment shown in

2

FIGS. 1, 2, and 3 includes a body having semi-cylindrical cooperating sections 24 and 25 which are connected at their rear ends by curved tongue and groove hinge parts or portions defining displaceable hinges 27 and which are formed with flared forward end portions 28 having concentric grooves 29 and 30 in their front or end faces. Inwardly of the forward ends of the sections 24 and 25 are mating recesses 31 which cooperate to define a chamber for receiving a normally compressed helical spring 32. As best seen in FIG. 1, the sections 24 and 25 snugly receive the forward end of the probe 21 and effectively seal the opening 23 to prevent the entry of foreign substances into the interior of the probe.

Normally retaining the sections 24 and 25 in mating relation, for defining the seal, is a deposit of low melting point alloy 33, such as "Cerrobend," produced by the Cerro de Pasco Corporation, New York, New York. The composition of "Cerrobend" is 50% bismuth, 26.7% lead, 13.3% tin, and 10% cadmium, and its melting temperature is 158° F. Other properties of "Cerrobend" are as follows:

Approximate specific heat liquid	.....	.040
Approximate specific heat solid	.....	.040
Approximate latent heat	.....	14
Approximate coefficient of thermal expansion	.....	.000022° C.
Yield temperature	.....	158
Weight lbs./in. ³	.....	.339
Tensile lbs./in. ³	.....	5990
Maximum load 30 sec. lb./in. ²	.....	10,000

The deposit 33 completely fills the grooves 29 and 30 and covers the outer end faces of the sections 24 and 25 for retaining the sections in assembled relation, the hinge 27 securing the corresponding rear end portions of the sections 24 and 25 against displacement.

In use, when a missile utilizing the seal constructed as described above is fired, air flow at high temperature will impinge on the deposit 33 for melting the same, when continuing air flow, accompanied by the expanding effort of the spring 32, will urge the sections 24 and 25 outwardly to the positions shown in dotted lines in FIG. 1. Further outward movement, which will be brought about by the aforementioned air flow, will cause separation of the hinge 27, when the sections 24 and 25 will be blown clear of the missile. Air flow may then enter the opening 23 in the probe 21.

In lieu of the concentric grooves 29 and 30, parallel rectangular grooves may be employed; such grooves are shown at 34 and 35 in FIG. 3. Also, if desired, supplemental sealing means may be placed over the opening 23 within the sections 24 and 25, as shown in dotted lines at 36 in FIG. 1.

Obviously many modifications and variations of the present invention are possible in the light of the above teachings. It is therefore to be understood that within the scope of the appended claims the invention may be practiced otherwise than as specifically described.

What is claimed is:

1. In combination with an aerial missile having a nose probe formed with an opening, a displaceable protective device comprising, a pair of semi-cylindrical sections fitting in mating relation about the probe, said sections having hinge portions at their rear ends cooperating to define a separable hinge, and having flared forward end portions with front faces, complementary concentric semi-circular grooves in said faces, and a retaining means for holding said sections in mating relation, said means comprising a mass of alloy possessed of low melting point characteristics and disposed on said front faces and in said grooves in a manner whereby said retaining means

will be rendered inoperative to further restrain said sections due to the melting of said mass which occurs with the increase in temperature created by the friction effects of air flow relative thereto and thereafter allow the force effects of said air flow to separate said sections and to remove them from the probe.

2. In combination with an aerial missile having a nose probe, a displaceable protective device comprising, a pair of mating semi-cylindrical sections having hinge portions connecting said sections at their rear ends, the forward portions of said sections being flared and terminating in flat faces having spaced grooves therein, a spring interposed between said mating sections and urging said sections apart, and a retaining means for holding said sections in mating relation comprising a mass of alloy having low melting point characteristics and disposed on said faces and in said grooves in a manner whereby said retaining means will be rendered inoperative to restrain said sections due to the melting of said mass which occurs with the increase in temperature created by the friction effects of air flow relative thereto and thereafter allow said spring to separate said sections.

3. A displaceable protective device for protecting nose probe openings in vehicles traveling through a fluid me-

15 dium comprising, a pair of mating semi-cylindrical sections having hinge portions defining a displaceable hinge connecting said sections at corresponding rear ends, said sections being in mating relation and having a blunt end, said end having grooves therein, and a mass of alloy having low melting point characteristics disposed on said end and in said grooves in a manner normally retaining said sections in mating relation and whereby the fluid flow effects occurring with melting of said mass due to a temperature rise occasioned by air movement relative to said sections will free said sections for displacement from the probe.
